ASH TRAY

Filed March 27, 1931

Albert Heise
INVENTOR:
By Victor J. Evans & Co.
HIS ATTORNEYS

UNITED STATES PATENT OFFICE

ALBERT HEISE, OF CHICAGO, ILLINOIS

ASH TRAY

Application filed March 27, 1931. Serial No. 525,838.

This invention relates to certain novel improvements in ash trays, and has for its principal object the provision of an improved construction of this character which will be 5 highly efficient in use and economical in manufacture.

It is an object of this invention to provide an ash tray and a supporting arm therefor which is adapted to be pivotally mounted on 10 the underside of a table, such, for example, as a card table, or other object, so that the ash tray may be swung in a horizontal plane.

Another object of the invention is to provide a latching arrangement for detachably 15 mounting the ash tray on its supporting arm.

Other objects will appear hereinafter.

The invention consists in the novel combination and arrangement of parts to be herein- 20 after described and claimed.

The invention will be best understood by 25 reference to the accompanying drawings showing the preferred form of construction, and in which:

Fig. 1 is a perspective view of a preferred 30 form of construction of the invention as associated with a table or the like which is schematically shown;

Fig. 2 is a longitudinal vertical section 35 through the invention as shown in Fig. 1;

Fig. 3 is a bottom plan view on the line 3—3 40 in Fig. 2; and

Fig. 4 is an end elevational view on the line 4—4 in Fig. 1.

In the drawings, wherein a practical embodiment of the invention is illustrated, a 45 table, chair or other like object is schematically indicated in dotted lines at 10, Fig. 1, and the lower or bottom side at 11.

The invention provides an arm 12 which is 50 pivotally connected, by means of a suitable connecting element 13, to a cross arm 14 in which are provided holes 15 through which screws or the like may be inserted to secure the cross arm 14 to the underside of the table 55 10. On the upper side of arm 12, at the rear of plate 14, is a boss 16, and in the cross arm 14 are two holes 17, one at each side of arm 10, the purpose of which will be explained hereinafter.

An ash tray is indicated at 18 and includes

a bottom wall 19 and upstanding wall 20. In the wall 20 diametrically aligned slots 21 are provided below bottom wall 19 and through these slots the arm 12 is extended.

A notch 22 is provided in the arm 12, at 55 the end opposite the cross arm 14, and pivotally mounted on the outside of the wall 20, as at 23, is a latch element 24.

In use the cross arm 14 will be secured to the bottom side of the card table top 14 or other object by screws inserted through countersunk holes 15, and the arm 12 will be extended through both slots 21 and the latch 24 disposed in notch 22, thereby to detachably mount the ash tray on the arm 12, since by 60 disengaging the latch 24 from notch 22 the tray 18 may be slidably moved off the arm 12, toward the right, as seen in Figs. 1 to 3.

When the cross arm 14 is secured to the lower side of the table top 10, the tray 18 and arm 12 may be pivotally moved in a horizontal plane, about the element 13 as a pivot, and the arm 12 and tray 18 may be held in a position at an angle with respect to the edge 70 25 of top 10 by forcing the boss 16 under cross arm 14 so that the boss 16 will snap into one of the holes 17. To disengage boss 16 from either hole 17, a slight upward pressure on arm 12 will suffice, plus movement of arm 12 in a horizontal plane.

Extending across the tray 18 is a bridge 26 in which are perforations or holes 27 and this bridge 26 is detachably supported on the rim 28 of the tray by means of the ears 29 upon which a cigarette, cigar, or the like may be extinguished by inserting the lighted end into one of the holes 27 which will snuff out the cigarette by cutting off the air supply thereto.

The invention provides a convenient article for smokers and is particularly adaptable for use in connection with card or other tables, reading tables, chairs, etc.

While I have illustrated and described the preferred form of construction for carrying my invention into effect, this is capable of variation and modification without departing from the spirit of the invention. I therefore, do not wish to be limited to the precise details of construction set forth, but desire 95 100

to avail myself of such variations and modifications as come within the scope of the appended claims.

Having thus described my invention, what I claim as new and desire to protect by Letters Patent is:

1. In smoker's articles, an ash tray having diametrically aligned slots formed in the side wall thereof, a latch element pivotally mounted on said side wall adjacent one of said slots, an arm adapted to be inserted through, and with portions projecting from, both of said slots, one of said portions having a notch formed therein in which said latch element is adapted to be disposed whereby to detachably mount said tray on said arm, and means for securing the other of said arm portions to a supporting member.
2. In smoker's articles, an ash tray including an upstanding side wall and a bottom member raised above the lower end of said wall, said wall having diametrically opposed and aligned slots formed therein below said bottom member, a latch element pivotally mounted on said wall adjacent one of said slots, an arm adapted to be inserted through, and including portions projecting from, each of said slots, one of said arm portions having a notch formed therein in which said latch element is adapted to be engaged whereby to detachably mount said tray on said arm, and means for securing said arm to a supporting member.
3. In smoker's articles, an ash tray including an upstanding side wall and a bottom member raised above the lower end of said wall, said wall having diametrically opposed and aligned slots formed therein below said bottom member, a latch element pivotally mounted on said wall adjacent one of said slots, an arm adapted to be inserted through, and including portions projecting from, both of said slots, one of said arm portions having a notch formed therein in which said latch element is adapted to be engaged whereby to detachably mount said tray on said arm, and means for pivotally securing said arm to a supporting member for movement of said arm and tray in a horizontal plane, said means including an apertured cross arm pivotally connected to said first named arm and adapted to have securing elements inserted therethrough into said supporting member.
4. In smoker's articles, an ash tray including an upstanding side wall and a bottom member raised above the lower end of said wall, said wall having diametrically opposed and aligned slots formed therein below said bottom member, a latch element pivotally mounted on said wall adjacent one of said slots, an arm adapted to be inserted through, and including portions projecting from, both of said slots, one of said arm portions having a notch formed therein in which said latch element is adapted to be engaged whereby to

detachably mount said tray on said arm, and means for pivotally securing said arm to a supporting member for movement of said arm and tray in a horizontal plane, said means including an apertured cross arm pivotally connected to said first named arm and adapted to have securing elements inserted therethrough into said supporting member, a boss on the upper side of said first named arm, and said cross arm having holes formed therein into which said boss may be snapped to hold said first named arm at a predetermined angle with respect to said supporting member.

5. In smoker's articles, an ash tray including an upstanding side wall and a bottom member raised above the lower end of said wall, said wall having diametrically opposed and aligned slots formed therein below said bottom member, a latch element pivotally mounted on said wall adjacent one of said slots, an arm adapted to be inserted through, and including portions projecting from, each of said slots, one of said arm portions having a notch formed therein in which said latch element is adapted to be engaged whereby to detachably mount said tray on said arm, and means for pivotally securing said arm to a supporting member for movement of said arm and tray in a horizontal plane, said means including an apertured cross arm pivotally connected to said first named arm and adapted to have securing elements inserted therethrough into said supporting member.

6. In smoker's articles, an ash tray including an upstanding side wall and a bottom member raised above the lower end of said wall, said wall having diametrically opposed and aligned slots formed therein below said bottom member, a latch element pivotally mounted on said wall adjacent one of said slots, an arm adapted to be inserted through, and including portions projecting from, each of said slots, one of said arm portions having a notch formed therein in which said latch element is adapted to be engaged whereby to detachably mount said tray on said arm, and means for pivotally securing said arm to a supporting member for movement of said arm and tray in a horizontal plane, said means including an apertured cross arm pivotally connected to said first named arm and adapted to have securing elements inserted therethrough into said supporting member, a boss on the upper side of said first named arm, and said cross arm having holes formed therein into which said boss may be snapped to hold said first named arm at a predetermined angle with respect to said supporting member.

In testimony whereof I affix my signature,
ALBERT HEISE.
